(57) **CLAIM**

The ornamental design for a mobile phone shell, as shown and described.

DESCRIPTION

FIG. 1 is a front, right, top perspective view of a mobile phone shell showing our new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a partial enlarged view of the encircled area 9 of FIG. 1; and,

FIG. 10 is a second front, right, top perspective view thereof, shown in a state of use.

The broken lines falling on the interior surfaces of the mobile phone shell in FIGS. 1, 2, 8 and 9 depict portions of the article that form no part of the claimed design. The broken line circles included in FIGS. 1 and 9 are provided for the purpose of indicating the portion included in the partial enlarged view and form no part of the claimed design. The broken lines depicting a mobile phone in FIG. 10 represent environmental subject matter included for the purpose of demonstrating a usage state, and form no part of the claimed design.

1 Claim, 8 Drawing Sheets
